ABSTRACT OF THE DISCLOSURE

Apparatus comprising a rotary head carrying a plurality of finning rolls. The rolls are driven by planet gears which revolve about a substantially stationary sun gear. The finning rolls may be moved radially into and out of operative position while the machine is running. Special lubricating passages are provided in the rotating structure.

BRIEF SUMMARY OF THE INVENTION

In accordance with the present invention there is provided a fin rolling machine including an input tube into which tubing or rod to be provided with fins is advanced. The input tube has a portion constituting a sun gear and is connected to means for effecting accurately adjusted slow rotation in either direction.

The machine includes rotary structure adapted to be driven at substantial speeds including a plurality of arbors adapted to support finning discs or rolls thereon. The arbors are independently mounted on the rotating structure for substantially radial adjustment between inwardly disposed positions in which the finning discs or rolls engage the work piece, and outward positions in which the peripheries of the finning discs are clear of the work piece. Means are provided for effecting substantial radial in and out movement of the finning tools during continued rotation of the rotating structure and during advance of tubular or rod-like work pieces, to provide for initiation and termination of a finning operation intermediate the ends of the work piece.

More specifically, the means for mounting the arbors for radial adjustment comprises pivoted brackets and a camming device movable generally parallel to the axis of advance of the work piece to force the finning tool arbors inwardly. Outward movement of the arbors to idle position may depend on centrifugal force developed by rotation of the rotary structure or special resilient means, or a combination of both.

Inasmuch as the machine necessarily has a relatively large and complicated rotary structure on which gears and finning roll arbors are provided, the problem of lubricating the bearings for the gears and arbors is solved by the provision of communicating lubricant passages extending longitudinally of the rotary structure.

BRIEF DESCRIPTION OF THE DRAWINGS

FIGS. 1A and 1B together constitute a vertical section through the fin rolling apparatus, with some parts rotationally displaced for clarity, the sections designated A, B, C, and D being taken on section lines correspondingly designated in FIGS. 11, 12, 13 and 3 respectively.

FIG. 2 is a composite longitudinal sectional view, the portion 2A of which is a sectional view on the line 2A—2A, FIG. 14; and the portion 2B of which is a sectional view on the section line 2B—2B, FIG. 14.

FIG. 3 is an end view of the apparatus.

FIG. 4 is a sectional view on the line 4—4, FIG. 1B.

FIG. 5 is a sectional view on the line 5—5, FIG. 1A.

FIG. 6 is a sectional view on the line 6—6, FIG. 1A.

FIG. 7 is a sectional view on the line 7—7, FIG. 1A.

2

FIG. 8 is a sectional view on the line 8—8, FIGS. 1A and 1B.

FIG. 9 is a sectional view on the line 9—9, FIG. 1B.

FIG. 10 is a sectional view on the line 10—10, FIG. 1B.

FIG. 11 is a sectional view on the line 11—11, FIG. 1B.

FIG. 12 is a sectional view on the line 12—12, FIG. 1B.

FIG. 13 is a composite sectional view, the portion 13A being taken on the line 13A—13A, FIG. 4; the portion 13B being taken on the lines 13B—13B, FIG. 4; and the portion 13C being taken on the line 13C—13C, FIG. 4.

FIG. 14 is a diagrammatic view illustrating the arrangement of gearing, looking in the direction of the arrow 14, FIG. 1B.

DETAILED DESCRIPTION

The tube or rod finning machine comprises a stationary base 10 having bearing stands 12, 14, 16 and 18, each of which is provided with bearing structure indicated generally at 20. There is also provided a stand 22 provided with a bearing structure indicated generally at 24 which supports an elongated work inlet tube 26 for rotation. The tube 26 is splined as indicated at 28 and is connected to drive means indicated diagrammatically at 30 which is accurately adjustable as to speed so as to drive the tube at an accurately controlled forward or reverse speed as required by conditions subsequently to be described.

Mounted within the several bearing structures 20 previously described is rotary structure, the parts of which will be described in detail. The rotary structure includes a drive pulley 32 adapted to be driven by a belt 34 at substantial speeds. It will be observed that the pulley 32 is keyed to a first rotary member 36 which is supported in bearings 20 provided in the pedestal or stand 12 at one end and which has a reduced end portion 38 which is received within a generally annular second rotary member 40. The rotary member 40 has a reduced end portion 42 extending into a substantially elongated rotary member 44. The forward or inner end of the tube 26 extends through rotary members 36 and 40 and into the end of the elongated third rotary member 44. A bearing 46 is provided intermediate the tube 26 and the end of the rotary member 44.

The forward end of the tube 26 is enlarged as indicated 45 and has external gear teeth formed thereon as indicated forming a sun gear 50 for the purpose of driving a planetary transmission, subsequently to be described.

Connected to the forward end of the third rotary member 44 (the right hand end as seen in FIGS. 1A and 1B) 50 is a fourth rotary member 54 and a fifth rotary member 56. A sixth rotary member 58 is connected to the fifth rotary member 56, the members 44, 54, 56 and 58 all being interfitting by annular rabbet connections indicated at 60 in FIG. 1B. These parts are assembled together and 55 are interconnected to the rotary member 40 by a plurality of assembly rods 62 having threaded ends 64 threaded into tapped openings in the second rotary member 40. The members are suitably doweled together as indicated at 66. Moreover, the members are provided with matching oil 60 passages 68. The forward end of the sixth rotary member 58 has a recess 74 which receives the end of a finning head 76, the finning head being driven by the front or sixth rotary member 58 by a drive key 78. The bearing 20 carried by the stand 16 supports the forward end of the 65 rotary member 58 and the forward end of the finning head is supported by bearing structure 20 carried by the front stand 18.

Mounted on the finning head 76 are three finning devices 80, details of which are better seen in FIGS. 4 and 13. The finning devices 80 comprise brackets 82 pivoted to the finning head 76 by pivot shafts 84. Brackets 82 have tubular portions 86 in which are mounted shafts 87 of

arbors 88. The arbors 88 at their outer ends are adapted to carry finning rolls 90 in the form of a multiplicity of finning discs as is well understood in the art. The shaft 87 has its inner end portion 92 extending into a universal drive unit 94 through which it is driven from a shaft constituting the output of planetary gearing which will subsequently be described.

Means are provided for effecting substantially radially inward and outward movement of the finning tools 90 so as to move the finning discs carried by the tools into the advancing tubular or rod-like work piece and to withdraw or permit outward displacement of the finning tool while the machine is in operation. This permits a length of unfinned tube for example, to be advanced axially through the finning head without formation of fins thereon. At a desired point spaced rearwardly from the advancing unfinned end portion of the tube, fin formation is initiated by simultaneously camming the finning tools inwardly while the finning head continues its rotation about the axis of the tube.

The foregoing is accomplished by providing on each of the tubular portions 86 of the brackets 82 cam blocks 96 having inclined camming surfaces 98 engageable by camming rollers 100 mounted on a shaft 102 extending between ears 104 carried by a camming ring 106 which is longitudinally slideable from the position shown in full lines in FIG. 1B leftward to the position indicated in dotted lines in the figure.

The ring 106 carries the inner race 108 of the ball bearing 20 intermediate the stands 16 and 18, and the outer race 110 is carried by a support 112 having laterally extending ears 114 connected to piston and cylinder devices indicated generally at 116 fixedly mounted on posts 118 extending upwardly from the base 10. When fluid pressure is admitted to the cylinders of piston and cylinder devices 116 the support 112 is shifted axially of the machine, carrying the rotatable ring 106 therewith. When the ring 106 is moved from the left to the position shown in FIG. 1B the roller 100 acting against the inclined cam surface 98, will cam the tubular portions 86 of the brackets inwardly to finning position. Since the bearings intermediate the races 108 and 110 provide for free rotation of the ring 106, the rollers 100 revolve with the cams 96 and the radial position of the finning devices 80 may be changed during continued operation of the machine.

During operation of the machine centrifugal forces urge the finning devices 80 outwardly and their outwardly displaced position is determined by cams 98 and rollers 100. Their inward position is similarly determined by the cam and rollers and preferably, resilient means such as the rubber pads 107.

The foregoing constitutes a very important advantage inasmuch as in tube finning it is often necessary to provide a length of finned tubing intermediate plain or unfinned portions. With the present arrangement, by properly controlling the admission of fluid to the piston and cylinder devices 116, the finning operation may be initiated and terminated as desired during continued advance of the tubing through the apparatus. Of course, it will be understood that where the finning operation is depended upon for effecting axial advance of the tubing, the tubing must be advanced by other means while the finning devices 80 are in radially outwardly displaced idle position.

In order to limit movement of the finning devices 80, means are provided to correspondingly limit the axial movement of the support 112 and this means constitutes an abutment 120 carried by the finning head 76, movable in an axially extending slot 122 provided in the ring 106.

As indicated at the outset, means are provided for revolving the finning devices about the axis of the tubing and also for effecting powered drive rotation of the finning discs 90. It will be understood that when the speed of rotation of the finning rolls or discs 90 is properly correlated to the speed of their revolution in orbital path about the axis of the tubing, fins will be produced on the

tubing and the tubing will be advanced axially without imparting any rotation whatsoever to the tubing. This relationship is however a delicate one and requires accurately controlled means for effecting changes in the relative speed of rotation and revolution of the finning tools or discs. This means, as previously described, comprises a drive means for the shaft 26, the inner end of which is formed with teeth to constitute a sun gear at 50. This provides the most efficient finning operation. In the past it has been usual to provide for rotation of the tube as a consequence of its engagement with the finning discs or rollers, or conversely, to provide for rotation of the rolls as a consequence of their engagement with the tube. In the present case however, neither drives the other and the tube is advanced without rotation while the finning discs are given the proper rotation in accordance with their orbital movement about the axis of the tubing. A second very important advantage of the construction just described is that since the tubing is not required to rotate, it may be advanced from coils or rolls which in turn may be stationary as regards rotation about the axis of advance of the tubing.

The mechanism for effecting rotation of the finning discs about their axes as a result of the rotation of the finning head 76 about its axis, will now be described.

In FIG. 2 there is shown a simplified construction in which the various gears are illustrated as rotationally displaced to provide a clear picture of the drive between the various gears. This figure may be compared with FIG. 30 14. It will be observed that the sun gear 50, which for the time being may be considered as stationary, is in mesh with a plurality, preferably three, planet pinions 124 formed on an elongated pinion member 125. The pinions 124 have reduced ends 126 journaled within appropriately formed recesses 128 in the third rotary member 44. Formed integrally with the pinion 124 is a second pinion 130 and beyond the pinion 130 the part is reduced as indicated at 132 and is journaled within the fourth rotary member 54.

40 Elongated double pinion members 134 are provided each having pinion portions 136 in mesh with the planet pinions 130 and having additional planet pinions 138. Pinion members 134 have reduced end portions 140 journaled within the rotary member 44, and reduced end portions 142 journaled within the rotary member 58.

45 Planet pinions 144 are provided in mesh with the pinions 138 and have reduced end portions 146 journaled within rotary member 56 and reduced end portions 148 journaled in rotary member 58.

Accordingly, the drive from the substantially stationary sun gear 50 is through pinions 124, 130, 136, 138 to the pinion 144. The pinion 144 has reduced an extension 150 of non-circular cross-section which extends into the universal joint 94 previously referred to and which is therefore effective to provide for rotation of the shaft 87 which in turn drives the finning rolls 90.

50 Reference has previously been made to the difficulty of providing for lubrication of the multiplicity of rotary parts carried by the rotary finning head 76. For this purpose interior communicating lubricant passages are provided as will now be described. Referring first to FIGS. 1A and 1B, considered in conjunction with FIG. 2, in which latter figure the parts are circumferentially displaced for clarity, an inlet lubricant fitting 152 is provided which communicates with an annular space 154 formed in the stationary stand 22. The first rotary member 36 is provided with a plurality of longitudinally extending oil passages 156 which communicate with an annular oil passage 158 formed in the second rotary member 40. The passage 158 communicates with an annular passage 160 which communicates through an inclined passage 162 with the passages 68 extending longitudinally of the third rotary member 44. In addition, the passage 160 communicates through a plurality of axially extending passages 164 with oil passages 166 extending longitudinally through the pinion members 134. Also, oil pas-

sage 160 communicates through passages 168 with passages 170 extending longitudinally through elongated pinion members 125.

Oil passages 68 formed in the sixth rotary member 58 are connected to external tubular fittings 174 which are connected by external conduits 176 to the finning head 76 and thence with longitudinally extending oil passages 178 formed in the finning head 76 which in turn communicate with oil passages 180 leading to the journal for the shaft 87 received in the tubular portion 86 of the support brackets 82.

It will be understood that small lubricant passages such as illustrated at 182 and 184 in FIG. 2, lead to the journals and that the shafts within the journals are provided with helical oil grooves as indicated in dot and dash lines in several of the figures. No effort has been made to illustrate all of these oil passages but they will be provided as necessary to produce an adequate supply of lubricant to the journals.

In operation the belt 34 drives the assembly of rotary members, the finning head 76 and the adjustable finning tools 90 in such a way as to cause the finning tools to revolve around the tube or rod on which the fins are to be provided. At the same time the finning rolls are positively driven by the planetary gearing including the substantially stationary sun gear 50. The tube is observed during the finning operation and if it progresses slowly in either direction as a result of a difference between the actual speed of rotation of the finning rolls and the theoretically correct speed of rotation thereof, the drive means 30 is adjusted to effect a slow compensating rotation of the sun gear 50 in the appropriate direction to vary the speed of rotation of the finning rolls so that the tubular work piece advances axially without rotation.

The absence of torsional stress between the finning rolls and the work piece, as a result of powered rotation and orbital movement of the finning rolls, permits finning operations which heretofore have not been commercially feasible.

In operation, plain tubing may be advanced through the finning devices without forming fins thereon and at any desired zone on the tubing the finning rolls may be cammed inwardly into operative relation to initiate and continue formation of fins on the tube. The operation results in axial advance of the tube without rotation and when a desired length of finned tubing has been produced, the piston and cylinder devices 116 may be operated to permit radially outward movement of the finning heads to inoperative position.

Continued rotation of the assembly of rotary members may be continuous with intermittent finning as desired, and proper lubrication of the parts which rotate independently within the rotary structure is provided at all times.

The drawings and the foregoing specification constitute a description of the improved apparatus for rolling fins on non-rotating tubes or rods in such full, clear, concise and exact terms as to enable any person skilled in the art to practice the invention, the scope of which is indicated by the appended claims.

What we claim as our invention is:

1. Tube finning apparatus comprising a base, an elongated tubular member through which a tube to be finned is advanced, bearing means on said base supporting the tubular member adjacent its rear end for rotation about its longitudinal axis, the forward end of said tubular member having a sun gear thereon, an elongated planetary gear housing having a first set of planet pinions in mesh with said sun gear, bearing means on said base supporting the rear end of said gear housing for rotation, bearing

means intermediate the forward end of said tubular member and the rear end of said gear housing supporting the forward end of said tubular member for rotation, an elongated finning head connected to the forward end of said gear housing for rotation therewith, bearing means on said base supporting the forward end of said gear housing for rotation, bearing means on said base supporting the forward end of said finning head for rotation, a plurality of fin roll support drive shafts carried by said head for rotation therewith, means connecting said shafts to said first set of planetary pinions for rotation thereby, and independently movable drive means for rotating said gear housing and finning head, and said tubular member and sun gear.

5 15 2. Apparatus as defined in claim 1 in which the pinions of said first set of planetary pinions are formed on first elongated pinion members, said members having a second set of pinions thereon, and a third set of pinions in mesh with the second set of pinions and included in the 20 means connecting said first set of planetary pinions to the roll support drive shafts.

3. Apparatus as defined in claim 2 in which said third set of pinions are formed on second elongated pinion members having a fourth set of pinions thereon, and a 25 fifth set of pinions in said housing in mesh with said fourth set of pinions and included in the means connecting said first set of pinions to the roll support drive shafts.

4. Apparatus as defined in claim 1 in which said tubular member includes an elongated oil passage extending therethrough and said pinion housing includes an annular chamber in communication with the forward end of said passage, the second passage extending from said chamber to the forward end of said housing, and means connecting said second passage to lubricating passages in said head.

35 5. Apparatus as defined in claim 4 in which said first elongated pinion members are tubular and constitute oil passage means for carrying lubricating oil to said fifth set of pinions.

40 6. Apparatus as defined in claim 4 in which said pinion housing comprises a multiplicity of sections separated generally along planes radially disposed to the axis of rotation, said sections being separable to provide for assembly of the pinion sets therein, and provided with 45 matching oil passages for carrying oil forwardly therethrough for lubrication of said finning head.

7. Apparatus as defined in claim 1 in which said roll support drive shafts are elongated and carry fin rolls at their forward ends, the rear ends of said drive shafts being pivotally and driveably connected to said fifth set 50 of pinions for rotation thereby, and cam means for rocking said shafts about the rear pivot connections thereof to provide for substantially radial in and out displacement of the finning rolls.

8. Apparatus as defined in claim 7 in which the connections between the rear ends of said drive shafts and said fifth set of pinions comprises universal drive units.
